APPARATUS FOR CONNECTING CONDUIT
SECTIONS

James N. Ice, Martins Ferry, Ohio, assignor to a trusteeship composed of himself, Alexander Best, and Samuel K. Frank, all of Wheeling, W. Va., as trustees

Original application November 30, 1938, Serial No. 243,257. Divided and this application August 3, 1939, Serial No. 288,245

2 Claims. (Cl. 81—15)

This invention is directed to an improved tool designed for permanently connecting the meeting ends of conduit pipe sections and providing in such connection a permanent metal seal. This 5 application is a division of my application filed November 30, 1938, Serial No. 243,257, now issued as Patent Number 2,192,914, dated March 12, 1940.

The primary object of the present invention is 10 to provide a coupling for the meeting ends of tubular sections and involving a sleeve member to overlie and bridge the meeting ends of tube sections, with the tool capable of acting on the sleeve in a manner to insure that the material of the sleeve is upset or grooved in annular form and with sufficient force to similarly and correspondingly indent the material of the tubes, whereby a permanent connection is made between the tubes and the interior of the tubes is permanently sealed against the admission of moisture or other deleterious matter.

The invention, therefore, consists in the provision of a tool by which the coupling is readily and conveniently formed with an annular depression which displaces the metal of the sleeve throughout the area of the depression, forming on the inner surface of the sleeve an annular projection which is itself forced into and forms an annular depression in the immediately underlying tube. As the formation results from a single operation of the tool, it is of course at once apparent that the projection on the inner surface of the sleeve is the sole means by which the receptive depression in the outer surface 35 of the tube is formed, and hence there is such an intimate and exact fit between this projected area on the sleeve and in the tube that there is provided an absolutely complete seal against the passage of moisture, water or the like in the tube.

40 The invention is illustrated in the accompanying drawing in which:

Figure 1 is a view in side elevation of the improved tool.

Figure 2 is a broken longitudinal section of the 45 same with a sleeve and tube shown in section in position between the jaws.

Figure 3 is an end view of the jaws.

Figure 4 is a longitudinal section showing the 50 coupling and conduit sections following completion of the operation.

Figure 5 is a view in elevation showing the improvement applied to a terminal box connector.

The improved tool comprises handles of which 55 1 may be termed the fixed handle and 2 the mov-

able handle. The fixed handle, as will be more clearly seen in Figure 2, is provided with a head 3 having adjacent its juncture with the handle a rounded upstanding projection 4. In advance of the projection 4, the head is provided with an extension 5 having a forwardly extending offset 6, the head in advance of the extension being provided with a roller base formation 7 in which is mounted forming rollers 8 and 9.

The handle 2 carries a head 10 which is pivotally connected to the handle at 11, the head being also pivotally connected at 12 to the upper end of the extension 5. The head 10 is recessed longitudinally to receive the end of the handle 2 and the upper end of the extension 5, and in this recess above the rollers 8 and 9 is mounted a single forming roller 13.

The handle 2 is adjacent its pivot formed with a depending section 14 terminating in a rounded point 15 designed in operation to bear upon the rounded surface of the projection 4, the relation of the parts being such that when the movable handle 2 is depressed with respect to the handle 1, the cooperation of the point 15 with the rounded surface of the projection 4 will rock the head 10 on its pivot 12 to cause the forming roller 13 carried by the said head to move toward the rollers 8 and 9.

It is to be particularly noted that the roller 8 is of larger diameter than the rollers 9 and 13, 30 which latter are of the same diameter, and that the rollers 8 and 9 have their operating planes on a line extending longitudinally of the head 3. In other words, the operative portions of the rollers 8 and 9 are substantially on a line forming the base of a triangle of which the roller 13 forms the apex, the triangle being substantially an equilateral triangle.

A block of rubber or other like resilient material 16 is interposed in the recess of the head 10 bearing between the upper wall of that recess and the top of the offset 6, this rubber or like block functioning to return the head 10 to normal position when the pressure on the handles 1 and 2 is relieved and the handle 2 permitted to move away from the handle 1.

The rollers 8, 9 and 13 are true rollers and not balls, and, as shown more particularly in Figure 3, they each comprise a body 17 movably fitted within the recesses in the respective heads and 50 rotatably supported upon a shaft 18 mounted in the walls of the heads. Each body of a roller has an annular rib 19, the juncture of which with the body is rounded and the peripheral edge of which is also rounded on the edges.

The tubes to be connected in end to end relation to form a conduit are indicated in Figure 4 at 20. The connecting sleeve is indicated in this figure at 21. This sleeve is previously formed 5 therein with an annular inwardly extending rib 22 against which the ends of the tubes 20 bear in the assembly of the parts.

It is the purpose of the present tool to unite 10 the sleeve and tube sections in a manner to secure them rigidly together and at the same time provide a sealing connection. This is effected by placing the connected tube sections and applied sleeve between the rollers 8 and 9, on the one hand, and 13, on the other, and then depressing 15 the handle 2 of the tool to cause the rollers to contact more or less with the surface of the sleeve. The sleeve elements are held against rotation and the tool is then rotated back and forth until they form in the sleeve, as at 23, an annular 20 channel which by reason of its inward projection 24 forms a corresponding and annular channel 25 in the tube.

The roller 8, which is of increased diameter with 25 respect to the rollers 9 and 13, serves to permit a more convenient and easy rotation of the tool, for as the rollers 8 and 9 are in line, the initial biting effort of any one roller tends to provide a slight demarcation in the sleeve which serves as a guide for the movement of the remaining rollers 30 and as the roller 8 is of greater diameter than the rollers 9 and 13, said roller 8 will serve to fit this demarcation to a somewhat increasing depth over the rollers 9 and 13 and maintain the channel formation in an accurate, positive annular line.

35 Thus, the rollers which finally cooperate to form the groove or channel initially serve somewhat different functions, first, in initially forming a slight depression and, second, in insuring that the rollers will operate within this depression in the further partial rotation of the tool.

In operation, it is understood that the tool is reciprocated in a rotary direction, being carried 45 at each rotation somewhat more than half the circumference of the sleeve. This will insure the accurate, even and easy formation of the channels in the sleeve and naturally the automatic interlocking channels in the tube.

Of course, the tool will be operated on each 50 portion of the sleeve overlying a particular tube end, so that both tube ends are interlocked and sealed in the manner described.

The tool may be utilized as applied to a terminal 55 box connector for use in electrical service for which the interconnected conduits are more particularly designed. This terminal box connector is shown in Figure 5 and is made of an over-size

conduit section 26 formed with an outstanding rib 27 to limit the application of the connector to the terminal box. The end of the conduit section is threaded at 28 to permit the application of the conventional securing nut on the inner side of the 5 terminal box. The tube section, which forms the end of the electrical conduit and is indicated in Figure 5 at 29, is inserted in the connector 26 and connection made through the provision of the channels, indicated at 30, by the use of the 10 tool described.

It is, of course, to be understood that the tool is available and practicable for any size of conduit used in normal construction. It is of importance to note that in addition to the sealing fit 15 the improvement provides a connection of great tensile strength forming in effect a perfect interlock resisting separation under a pull materially in excess of that to which the conduit would ever be subjected in use. Furthermore, with the 20 sections connected in the manner described, there is provided a continuous solid pipe or conduit which materially increases the life of the installation and one in which there is little possibility of a break or leak.

25 While the construction has been described in connection with a conduit designed for the connection of electrical wires and the like, it is of course to be understood that the apparatus is not to be restricted to this use, for such apparatus 30 may effectively serve for interlocking and sealing the meeting ends of pipes or the like designed, for example, for the passage of water or other fluid, under which circumstances it is more important as in such instances the conduit as a whole is 35 subjected at all times to the action of water or the like from within.

What is claimed to be new is:

1. An apparatus for providing an interlocking 40 sealing connection between the meeting ends of conduit sections, and a coupling overlying said conduit ends, comprising a tool having a fixed jaw and a movable jaw, said jaws presenting opposed flat parallel faces, a roller carried by one of the jaws, a pair of rollers carried by the opposing jaw, one of the pair of rollers being of a slightly increased diameter with respect to the remaining roller of the pair, the rollers operating in the same circumferential plane.

2. A construction as defined in claim 1 wherein 45 the single roller is carried by the movable jaw and the pair of rollers carried by the fixed jaw, the first roller on the fixed jaw, considered in the direction from the handles of the jaws, being the roller of the greatest diameter.
